UNITED STATES PATENT OFFICE.

HENRY J. DOUGHTY, OF PROVIDENCE, RHODE ISLAND.

FOXING FOR RUBBER BOOTS OR SHOES.

SPECIFICATION forming part of Letters Patent No. 722,823, dated March 17, 1903.

Application filed January 31, 1902. Serial No. 92,068. (No specimens.)

To all whom it may concern:

Be it known that I, HENRY J. DOUGHTY, a citizen of the United States, residing at Providence, in the county of Providence and State 5 of Rhode Island, have invented a new and useful Improvement in Foxing for Rubber Boots or Shoes, of which the following is a specification.

In the manufacture of rubber boots and 10 shoes strips are used to strengthen the joint between the uppers and the sole and also at other parts of the boot or shoe to ornament or strengthen the same. These foxing-strips were heretofore formed in sheets of rubber-coated textile material and required to be 15 cut into strips.

I have prepared an improved foxing-strip of pure-rubber compound, the inner face of 20 which adheres to the boot or shoe, while the outer surface enlarges from the edge where it unites with the vamp or the quarters gradually outward to the point where the foxing reaches the sole and then turns inward to the 25 end of the foxing. By this construction the foxing is materially strengthened at the intersection of the vamp and quarters with the sole of the boot or shoe.

The object of this invention is to facilitate 30 the use and handling of rubber foxing; and to this end the invention consists in forming the strips of foxing in the desired forms of rubber without the use of textile material and connect the several strips to each other by a thin knife-edge, as will be more fully 35 set forth hereinafter.

Figure 1 is an end view of a calender for 40 rolling my improved sheet of foxing-strips. Fig. 2 is a side view, on an enlarged scale, of parts of the two rolls of the calender, showing the manner of forming the foxing-strips with the thin connecting edges. Fig. 3 is a 45 perspective view of a sheet of foxing, indicating in broken lines the manner of separating the strips from the sheet by tearing. Fig. 4 is a perspective view of one of the torn-off foxing-strips.

In the drawings, A indicates the frame of the calender, and a the smooth roller, journaled in bearings supported on the frame of 50 the calender. The gear a' is secured to the shaft of the roller a and is operated by the pinion a², secured to a counter-shaft, to which the driving-pulley a³ is secured. The roller b is supported in sliding bearings. Part of

the roller b has the circumferential grooves 55 and beveled surfaces corresponding with the different forms of foxing-strips required. The grooves and beveled surfaces are separated by the knife-edges b²b², which when the ends of the roller b are in contact with the roller 60 a nearly touch the roller a, as is clearly shown in Fig. 2. b³b³ are the central enlargements of the foxing. The roller b is forced against the roller a by the screw c, and when the sheet of rubber is rolled the different strips forming the sheet adhere to each other by the thin film of rubber connecting the strips.

In the preferred form a sheet of foxing consists of a sufficient number of strips of the different forms required to trim one or 70 more rubber shoes. The sheet is not liable to injury in handling, and when the boot or shoe trimmer requires a strip of foxing the same may be readily torn from the sheet.

In arranging for the manufacture of the 75 foxing I form the roller b so that the foxing-strips successively required will be always at one of the two edges of the sheet and may be torn off successively as they are required.

In molding a rubber boot or shoe the fox- 80 ing made after my invention secures a more perfect line in the mold and prevents the sticking of the shoe to the mold.

Having thus described my invention, I claim as new and desire to secure by Letters 85 Patent—

1. The new article of manufacture consisting of a sheet composed entirely of unvulcanized-rubber compound and formed into strips of foxing connected by a film of the 90 compound, whereby the strips may be separated by tearing, as described.

2. Foxing-strips composed entirely of vulcanizable compound having a film on either end and a central enlargement, as described. 95

3. A sheet formed entirely of unvulcanized-rubber compound having a series of the different kinds of foxing required to trim rubber shoes connected together by films of the compound, as described. 100

In testimony whereof I have signed my name to this specification in the presence of two subscribing witnesses.

HENRY J. DOUGHTY.
